UNITED STATES PATENT OFFICE.

PETER DUENWALD, OF IRVINGTON, NEW JERSEY.

DISINFECTANT-HOLDER.

No. 927,132.

Specification of Letters Patent.

Patented July 6, 1909.

Application filed November 25, 1908. Serial No. 464,437.

To all whom it may concern:

Be it known that I, PETER DUENWALD, a citizen of the United States, residing at Irvington, in the county of Essex and State of New Jersey, have invented certain new and useful Improvements in Disinfectant-Holders; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in sanitary devices or appliances adapted for use in water-closets and urinals and constructed to hold or retain in place a suitable disinfecting device or appliance 20 which is especially adapted for use in connection with the bowl or hopper of a water-closet.

The present invention, therefore, has for its principal object to provide a novel, simple and cheaply made disinfectant-holder or appliance, which is readily applied to the bowl or hopper of any suitable shape, of a water-closet, or to the bowl of a urinal, the device being detachably fitted in place with 30 in the bowl, in which it is held by frictional or spring-engagement, and can be easily and quickly removed from the bowl for cleaning purposes.

A further object of this invention is to provide a disinfectant-holder made from suitable wire which is twisted in the form of a coiled spring, in which a disinfectant-material in the form of balls, tablets, or the like, is retained, and the coils of the spring having sufficient separable movement with relation to one another, so that in case of the need of a fresh supply of the disinfecting material, new disinfecting balls, tablets, or the like, can be readily forced between any two coils 45 of the spring-like element, for loading the said disinfectant-appliance.

Other objects of this invention not at this time more particularly enumerated will be clearly understood from the following detailed description of the same.

With the various objects of my present invention in view, the said invention consists, primarily, in the novel disinfectant-holder or appliance of the general character hereinafter set forth; and, the invention consists, furthermore, in the novel arrangements and

combinations of the various devices and parts, as well as in the details of the construction of the same, all of which will be herein-after more fully set forth, and then finally embodied in the clauses of the claim which are appended to and which form an essential part of this specification.

The invention is clearly illustrated in the accompanying drawings, in which: —

Figure 1 is a longitudinal vertical section of one form of water-closet bowl or hopper, and the disinfectant-holder or appliance embodying the principles of my present invention; and Fig. 2 is a horizontal section, on an enlarged scale, of the said bowl or hopper, said section being taken on line 2—2 in said Fig. 1, and showing the disinfectant-holder or appliance in plan. Fig. 3 is a detail vertical section taken on line 3—3 in said Fig. 2, said section being made on a still larger scale; and Fig. 4 is a horizontal section of a connecting member, and the respective end-portions of a piece of wire, upon which the spirally coiled disinfectant-holder is arranged, said holder, however, being omitted from this view, and the end-portions of the wire being slidably and adjustably connected with said connecting member. Fig. 5 is a horizontal sectional representation of another form of water-closet bowl or hopper, showing in connection therewith and in plan, a modified form of disinfectant-holder or appliance, said holder being made according to the principles of the present invention.

Similar characters of reference are employed in all of the above described views, to indicate corresponding parts.

Referring now to Figs. 1 to 4 inclusive of the drawings, the reference-character 1 indicates a suitably formed water-closet bowl or hopper, which is formed with a web 2 and an inwardly extending portion or enlargement 3, the various parts being made to provide an inlet-duct 4 and a discharge-duct or outlet 5. The reference-character 6 indicates the disinfectant holder or appliance, and the same comprises a suitable band or strip 7, usually a piece of wire, which is formed with the angularly made or bent and forwardly extending portions 8 and 9 and a connecting member or element 10. The free end-portions 11 and 12 of the band or strip 7 are preferably inserted in and passed through suitably arranged ducts or openings 14 and 15 of a suitably formed union or connecting member 13, substantially as shown in Figs. 2 and

4. the said end-portions 11 and 12 of the band or strip being slidably arranged in said ducts or openings 14 and 15, and being held in their adjusted relations to said union or connecting member 13 by means of frictional contact between the said parts. Encircling the main body-portions 16 and 17 of the said band or strip 7, are suitably formed holders 18 and 19, each holder being made in the form of a spirally coiled spring, between the coils of which are inserted, so as to be retained within the interior of each spring-member or element 18 and 19, suitable balls or tablets, as 20, composed of any desired disinfectant material or composition. To secure the disinfectant-holder or appliance, thus produced, in its operative position within and in frictional holding engagement with the inner surface-portions of the water-closet bowl or hopper 1, the connecting member or element 10 and the portions 8 and 9, are arranged against the enlargement 3 of the bowl or hopper, so as to register with the said enlargement, and by means of the proper adjustment of the end-portions 11 and 12 of the band or strip 7, with reference to the union or connecting member 13, the body-portions 16 and 17 and the spirally coiled holders 18 and 19 thereon will be made to conform to the inner oval shape or contour of the bowl or hopper 1, being retained in place by the frictional holding engagement of the parts, as will be clearly evident from an inspection of Figs. 1 and 2 of the drawings. The disinfectant balls or tablets 20 can be inserted in place, from time to time as required, by forcing them between the coils of the holders 18 and 19, without removing the disinfectant holder or appliance from within the bowl or hopper. The device or appliance can also be easily removed, when desired, from its operative position within the bowl or hopper, for cleansing the same when this becomes necessary.

45. In Fig. 5, I have shown another form of bowl or hopper, as 21, which has a circular sectional conformation, and is provided with a centrally disposed outlet 22 and a side-flush or water-inlet 23. In this case, the disinfectant-holder or appliance comprises a single strip or band 24, usually a piece of wire, having its end-portions 25 and 26 slidably and adjustably connected with a union or connecting-member 27, in the same manner as hereinafter set forth, a single and spirally coiled disinfectant-holder or element 28 encircling the said band or strip 24 in the manner represented in said Fig. 5 of the drawings.

50. From the foregoing description of my present invention, and from an inspection of the several figures of the drawings, it will be seen that I have produced a simply and cheaply constructed, as well as an effective disinfectant-holder or appliance, which is flexible so as to be applied to the inner contour of the

flush-out bowls or hoppers of water-closets, the arrangement and construction of the disinfectant-holding or retaining member or members being such, so that a perfect sanitary arrangement is provided, and the disinfectant-balls, tablets, or the like, are kept away from the bottom of the bowl or hopper, so that the disinfecting material is not flushed into the outlet of the bowl or hopper, with each flushing-out operation of the same. 70 75

While I have described my novel form of disinfectant-holder or appliance in connection with a bowl or hopper of a water-closet, and in which connection I prefer to use the same, it will also be evident that my novel form of 80 disinfectant-holder or appliance can just as readily be used with the bowls of urinals.

I am aware that some changes may be made in the general arrangements and combinations of the devices and parts, as well as 85 in the details of the construction of the same, without departing from the scope of my present invention as set forth in the foregoing specification, and as defined in the appended claims. Hence I do not limit my present invention to the exact arrangements and combinations of the devices and parts as described in the foregoing specification, nor do I confine myself to the exact details of the 90 construction of the said parts as illustrated in 95 the accompanying drawings.

I claim:

1. The combination with the bowl of a water-closet, of a disinfectant-holder within said bowl consisting of a strip, said strip being provided with a pair of bent and forwardly extending retaining portions, and a laterally extending connecting portion between said bent and forwardly extending retaining portions, said strip having free ends, 100 105 and a connecting means between the free ends of said strip.

2. The combination with the bowl of a water-closet, of a disinfectant-holder within said bowl consisting of a strip, said strip being provided with a pair of bent and forwardly extending retaining portions, a laterally extending connecting portion between said bent and forwardly extending retaining portions, said strip having free ends, 110 115 and a tubular connecting member to which said free ends are connected.

3. The combination with the bowl of a water-closet, of a strip within said bowl said strip being provided with a pair of bent and 120 forwardly extending retaining portions, a connecting member between said portions, and a spirally coiled disinfectant-holder encircling said strip.

4. The combination with the bowl of a water-closet, of a flexible strip within said bowl said strip being provided with a pair of bent and forwardly extending retaining portions, a connecting member between said portions, and a flexible and spirally coiled disinfectant- 125 130

- holder encircling said strip, adapted to conform to the inner contour of the bowl and adapted to receive and retain a disinfectant within said bowl.
5. The combination with the bowl of a water-closet, of a strip having free end-portions, means for adjustably connecting said free end-portions, and a spirally coiled disinfectant-holder encircling said strip.
10. The combination with the bowl of a water-closet, of a flexible strip within said bowl, said strip having free end-portions, means for adjustably connecting said free end-portions, and a flexible and spirally coiled disinfectant-holder encircling said strip, adapted to conform to the inner contour of the bowl and adapted to receive and retain a disinfectant within said bowl.
15. The combination with the bowl of a water-closet, of an inwardly extending enlargement, of a flexible strip within said bowl, said strip being formed with bent portions and a connecting element registering with said enlargement, and flexible and spirally coiled disinfectant-holders encircling portions of said strip.
20. The combination with the bowl of a water-closet formed with an inwardly extending enlargement, of a flexible strip within said bowl, said strip being formed with bent portions and a connecting element registering with said enlargement, and having free end-portions; means for adjustably connecting said free end-portions, and flexible and spirally coiled disinfectant-holders encircling 35 portions of said strip.
25. A disinfectant appliance consisting of a strip, and a spirally-coiled holder encircling said strip adapted to receive and retain a disinfectant.
30. A disinfectant appliance consisting of a strip formed with bent and inwardly extending retaining portions and a connecting element between said portions, and spirally-coiled holders encircling portions of said strip adapted to receive and retain a disinfectant.
35. A disinfectant appliance consisting of a strip formed with bent portions and a connecting element, and spirally-coiled holders encircling portions of said strip adapted to receive and retain a disinfectant, said strip having free end-portions, and means connected therewith for adjustably connecting said end-portions.
40. A disinfectant appliance consisting of a strip formed with bent portions and a connecting element, and spirally-coiled holders encircling portions of said strip adapted to receive and retain a disinfectant, said strip having free end-portions, and means connected therewith for adjustably connecting said end-portions.
45. A disinfectant appliance consisting of a strip formed with bent portions and a connecting element, and spirally-coiled holders encircling portions of said strip adapted to receive and retain a disinfectant, said strip having free end-portions, and means connected therewith for adjustably connecting said end-portions.
50. A disinfectant appliance consisting of a strip formed with bent portions and a connecting element, and spirally-coiled holders encircling portions of said strip adapted to receive and retain a disinfectant, said strip having free end-portions, and means connected therewith for adjustably connecting said end-portions.
55. A disinfectant appliance consisting of a strip formed with bent portions and a connecting element, and spirally-coiled holders encircling portions of said strip adapted to receive and retain a disinfectant, said strip having free end-portions, and means connected therewith for adjustably connecting said end-portions.
60. In testimony, that I claim the invention set forth above I have hereunto set my hand this 24th day of November, 1908.

PETER DUENWALD.
